UNITED STATES PATENT OFFICE.

JOHN B. DYAR, OF DETROIT, MICHIGAN.

DESIGN FOR RADIATOR ORNAMENTATION.

SPECIFICATION forming part of Design No. 18,440, dated July 10, 1888.

Application filed March 27, 1888. Serial No. 268,677. Term of patent 3½ years.

To all whom it may concern:

Be it known that I, JOHN B. DYAR, a citizen of the United States, and residing at Detroit, in the county of Wayne and State of Michigan, have invented and produced a new and original Design for Radiators or Radiator-Loops, of which the following is a specification, reference being had to the accompanying drawings, forming part thereof

10 Figure 1 is a perspective view of a radiator with my new design. Fig. 2 is an elevation of one of the loops detached.

The leading feature of my design consists in the general outline of the radiator-loop B, in 15 the cross-section of the radiator-loops, and in the ornamentation provided therefor. The ordinary form of radiator-loops as heretofore made was that of a tubular pipe rounded on top. Instead of that I design the top to form 20 the appearance of a table, A, where the loops are connected up into the radiator, thus dispensing with the ordinary top usually required to impart a finished appearance to the radiator; and this top may be either projected 25 beyond the sides of the radiator, as shown in Fig. 2, or be more or less contracted, as shown in Fig. 1. For the cross-section of the radiator-loop I adopt an egg-shaped or similar elongated form, and which, with its more 30 pointed side, is turned outward. The ornamentation which I apply to such faces of the loops which are exposed to the vision consists in the use of a flame ornament, D, applied to the lower portion of the radiator, and a smoke ornament, E, applied to

the upper portion of the radiator. The smoke ornament E is represented by a vertical series of scrolls gradually enlarging toward the top to represent the dispersion and expansion of the wreath of smoke. The flame 40 ornament consists of a more or less conventional design as generally used to represent flame. Between the two kinds of ornaments I generally provide the radiator with a plain surface to represent the gradual transition 45 from the heat into the smoke, as observed in the natural phenomenon of combustion. The base of the radiator I provide with some 50 convenient motive, such as the ornamental leaves E', to form a holder, basket, or other vessel from which the flames issue to the radiator-loops, provided the legs are integrally a part of this ornament. The radiator-loops may still more be improved in ornamental appearance by the art of bronzing or otherwise. 55

No claim is made herein to the configuration of the loop, as that forms the subject-matter of an application filed by me June 4, 1888, Serial No. 276,535.

What I claim as my invention is—

60 The design for the surface ornamentation of a radiator-loop herein shown and described, the same consisting of the flame ornament at the lower end of the loop and the smoke ornament at the upper end of the loop.

JOHN B. DYAR
